UNITED STATES PATENT OFFICE.

HARRY S. KUHN, OF WAYNESBORO, PENNSYLVANIA.

PIPE-VISE.

1,150,040.

Specification of Letters Patent. Patented Aug. 17, 1915.

Application filed October 5, 1914. Serial No. 865,106.

To all whom it may concern:

Be it known that I, HARRY S. KUHN, a citizen of the United States, residing at Waynesboro, in the county of Franklin and State of Pennsylvania, have invented a new and useful Pipe-Vise, of which the following is a specification.

The present invention relates to improvements in a pipe vise, one object of the present invention, being the provision of novel means whereby the movable jaw may be locked in any adjustment, by the simple manipulation of a pawl lock and a cam for actuating the same, the said pawl being adjustable relatively to the cam to permit of the desired quick action of the cam in moving the same into locking relation, the same being released by a spring.

A further object of the present invention, is the provision of a pipe vise provided with a plurality of gripping members which are readily insertible within the respective jaws, each gripping member being composed of two sections instead of made in a single member as is the usual practice.

A still further object of the invention, is the provision of means for adjusting the movable jaw of the vise, including primarily a removable toothed bar, in combination with a frame slidable thereupon which carries a spring released pawl, a manually controlled cam being provided to operate the pawl in locking relation.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings—Figure 1 is a view in plan of a hinged frame jaw vise constructed according to and embodying the present invention. Fig. 2 is a view in elevation taken from the right of Fig. 1. Fig. 3 is a section taken on line 3—3 of Fig. 1. Fig. 4 is a section taken on line 4—4 of Fig. 2. Fig. 5 is a perspective view taken from the inner end of the locking pawl. Fig. 6 is a detail elevation of the cam for actuating the pawl. Fig. 7 is a view similar to Fig. 1 showing the present invention applied to an open jaw pipe vise. Fig. 8 is a view taken from the

right of the vise as shown in Fig. 7, the movable jaw actuating means being shown in section. Fig. 9 is a section taken on line 9—9 of Fig. 7, the actuating member being removed. Fig. 10 is an enlarged detail sectional view through one of the jaws showing the gripping member in place. Fig. 11 is a perspective view of one of the gripping members removed. Fig. 12 is an end view taken from the inner edge of one of the gripping members.

Referring to the drawings and more particularly to the structure shown in Figs. 1 through 6, the numeral 1 designates the supporting member or base of the vise, which is adapted to adjustably connect the support B, which is set forth more in detail in my co-pending application filed even date here-with, Serial No. 865,108 and which will not be set forth in detail herein.

Carried by the base 1 is a pivotal connecting member 2, which by means of the pin 3 connects the member 4 thereto. The base 1 carries the fixed jaw J, while the member 4 carries the movable jaw J'. The member 5 of the member 4, is adapted to be connected at 6 to the base 1 and thus form a support at the opposite side for the movable jaw J', the pin 7 pivoting the locking member 8 in place, so that the recess 9 thereof will engage the projection or lug 10 of the base 1 and thus lock the pivoted member of the present device in place.

The adjusting member 11 for the movable jaw J' is threaded as at 13, being rotated by the bar 12 so that the support 14 therefor will permit of the longitudinal movement of the member 11 relatively to the sleeve 17 of the frame 4. The jaw J' is connected to the member 11 as illustrated in Fig. 3.

Adjustably mounted in the member 14 parallel to the member 11, is a cylindrical portion 15 of the bar 16, the same being held in fixed relation thereto by means of the set screw 17'. Thus as the member 11 is rotated, its carried member 14 will be slid therewith as will also the bar 16, said bar 16 being guided through the member 17 of the frame 4 which is provided with the rectangular opening 18 to prevent the rotation of the bar 16. The bar 16 is provided with the oppositely disposed toothed portions 19, which are adapted to coöperate with the toothed portion 20' of the pawl 20 disposed in the casing 17. This pawl 20 is provided with the adjusting screw 21 and with the

two parallel arms 22. These arms 22 fit astride of the cam 23, which is rotatably mounted in the member 17 so as to abut the arms 22 and the screw 21, to operate the 5 pawl 20 in opposition to its spring 24, which normally engages the lug 25 to hold the pawl 20 out of engagement with the bar 16. A sliding pin or bar 26 is employed to rotate the cam 23.

10 It will thus be seen that by rotating the stem or member 11, the jaw J' will be moved to or from the jaw J, and that when the same is in the desired adjustment, that upon manipulating the cam 23, the pawl 20 may 15 be operated against its spring 24 and thus have its teeth 20' placed in engagement with the toothed bar 16 so as to lock the bar 16 and consequently the member 11 against longitudinal movement.

20 By constructing the cam 23 and the screw 21 as illustrated, the movement of the pawl may be readily adjusted to act more quickly or slowly according to the projection of the screw 21.

25 In the construction in Figs. 7, 8 and 9, the cylindrical rod 27 which constitutes the support for the sliding frame 28, and for the adjustable jaw carrying frame 29, is provided. The adjustable frame 29 carries 30 the fixed jaw 30 while in order that the member 28 may be adjusted upon the support 27, the upper end of the support 27 is provided with screw threads 31, which co-operate with the threads 32 of the operating cap 33 which in turn is operated by the bar 34. The cap 33 is provided with the flange 35 which co-operates with the mutilated rim 36 of the member 28, which permits the cap 33 to be rotated and yet be fixed to the member 28. As the member 27 is permitted a 40 slight sliding movement through the member 28, it will be seen that the same may be adjusted to a slight degree upon the member 28. Adjustably held by the screws 37 with- 45 in the sleeve 38, is the cylindrical portion 15' of the bar 16', said bar 16' being threaded through the slidable frame 39, which carries the adjustable jaw 40, and the sleeve 41, which is slidably mounted upon the 50 cylindrical support 27. Carried in the frame 29 is the pawl 20^a, which is constructed and operated similarly to the pawl 20 heretofore described. It will thus be seen that by the manipulation of the handles 26 55 and 26' of the respective jaw vises, the adjustable jaws J' and 40 may be readily locked in the desired adjustment relatively to the fixed jaws J and 30, such action being exceedingly quick. The handle 26' is 60 limited in its releasing relation by means of the clip 42.

In the construction of gripping members as illustrated in Figs. 10, 11 and 12, the two sectional members 43 and 43' are employed, the same fitting within the respec- 65

tive sockets 44 of the jaw and being provided with the conical recesses 45 by means of which the screws carried by the respective jaws may engage and thus lock the same against outward displacement.

70 By making the gripping members 43 and 43' in sections instead of in a single member as is the usual practice, and seating them as illustrated in Fig. 10, within the recess of the jaw, it is apparent that the same may be readily removed for replacing, either as an entirety or in sections.

75 What is claimed is:—

1. A pipe vise, including a frame, a stationary and a movable jaw member carried thereby, a pipe gripping jaw mounted in each member, means for adjusting the movable jaw member relatively to the stationary jaw member, a toothed bar carried by the movable jaw member, an auxiliary frame surrounding the toothed bar, a spring released pawl mounted in the auxiliary frame and normally out of engagement with the toothed bar, manually controlled means for actuating the pawl to engage the bar and lock the movable jaw member in adjusted position, and coöperable means carried by the pawl and the manually controlled means for adjusting the relative portion of the pawl and manually controlled means to 90 regulate the action of the pawl.

2. A pipe vise, including a frame, a stationary and a movable jaw member carried thereby, a pipe gripping jaw mounted in each member, means for adjusting the movable jaw member relatively to the stationary jaw member, a toothed bar carried by the movable jaw member, an auxiliary frame surrounding the toothed bar, a spring released pawl mounted in the auxiliary frame and normally out of engagement with the toothed bar, manually controlled means for actuating the pawl to engage the bar and lock the movable jaw member in adjusted position, said pawl being provided with two spaced lugs, and a manually operated cam mounted in the auxiliary frame and disposed between the spaced lugs of the pawl, whereby as the cam is operated, the pawl is moved in opposition to the spring.

3. A pipe vise, including a frame, a stationary and a movable jaw member carried thereby, a pipe gripping jaw mounted in each member, means for adjusting the movable jaw relatively to the stationary jaw member, a toothed bar carried by the movable jaw member, an auxiliary frame surrounding the toothed bar, a spring released pawl mounted in the auxiliary frame and normally out of engagement with the toothed bar, manually controlled means for actuating the pawl to engage the bar and lock the movable jaw member in adjusted position, said pawl being provided with two spaced lugs, a manually operated cam 120

mounted in the auxiliary frame and disposed between the spaced lugs of the pawl, whereby as the cam is operated, the pawl is moved in opposition to the spring, and 5 adjustable means carried by the pawl for engagement with the cam to regulate the distance of movement of the cam in moving the pawl into rack engaging position.

4. A pipe vise, including a frame, a stationary and a movable jaw member carried thereby, a pipe gripping jaw mounted in each member, means for adjusting the movable jaw member relatively to the stationary jaw member, a toothed bar carried by the 15 movable jaw member, an auxiliary frame surrounding the toothed bar, a spring released pawl mounted in the auxiliary frame and normally out of engagement with the toothed bar, manually controlled means for

actuating the pawl to engage the bar and 20 lock the movable jaw in adjusted position, said pawl being provided with two spaced lugs, a manually operated cam mounted in the auxiliary frame and disposed between the spaced lugs of the pawl, whereby as the 25 cam is operated, the pawl is moved in opposition to the spring, and a screw adjustably mounted within the pawl between the arms thereof for engagement with the cam to regulate the coöperative action between 30 the cam and pawl.

In testimony that I claim the foregoing as my own, I have hereto affixed my signature in the presence of two witnesses.

HARRY S. KUHN.
